UNITED STATES PATENT OFFICE.

JEAN NÉPOMUCÈNE HOCHGESAND, OF PARIS, FRANCE.

PUMP FOR LIQUID OR GASEOUS BODIES.

SPECIFICATION forming part of Letters Patent No. 687,377, dated November 26, 1901.

Application filed May 12, 1899. Serial No. 716,471. (No model.)

To all whom it may concern:

Be it known that I, JEAN NÉPOMUCÈNE HOCHGESAND, engineer, of 200 Quai Jemmapes, in the city of Paris, Republic of France, have invented Improvements in Pumps for Liquid or Gaseous Bodies and for Various Uses, of which the following is a full, clear, and exact description.

The present invention has for its object an arrangement of single-valve pump reduced to the parts strictly necessary to insure an absolutely-regular delivery, at the same time obviating all injurious spaces and all loss due to the more or less uncertain working of the valves, and particularly of the suction-valve. This arrangement of pump enables all liquid or gaseous bodies—such as water, petroleum, oil, air, &c.—to be distributed in exactly-determined quantity, capable of being regulated at will and automatically by the action of a float or other regulating appliance, according to whether it is used for the automatic feeding of boilers or for the distribution of petroleum or of spirit of petroleum in oil-motors. My arrangement of pump may also be applied to the distribution of oil for the lubrication of engines and machines of all kinds, or as pneumatic pump, as air-compressor for inflating pneumatic tires, or as vacuum-pump, &c. My arrangement of pump consists, essentially, of a piston which moves in the interior of a movable cylinder, open at its lower part and moved during a part of the stroke of the piston by the frictional action of the packing of the latter, and of a fixed seat, on which the bottom of the cylinder is seated during the delivery period, this seat being provided with a passage fitted with escape-valve. On the rising of the piston, the cylinder, following the movement of the latter, is separated from its seat, so that there is communication between the exterior and interior of the cylinder, and consequently suction to the interior of the latter. On the contrary, on the descent of the piston, it becomes seated on its seat, so as to close all communication between the exterior and the interior, and the fluid sucked in is forced into the delivery-passage. The working of my arrangement of pump may therefore be divided into four periods: first, ascent of the cylinder and piston to establish communication between the

exterior and the interior of the cylinder; second, ascent of the piston alone or suction to the interior of the cylinder; third, descent of the cylinder and piston on application of the cylinder to its seat, so as to close all communication between the exterior and the interior of the cylinder, and, fourth, descent of the piston alone or delivery of the fluid sucked in.

In order that the invention may be more clearly understood, I have represented examples of the same in the drawings accompanying my specification.

In the accompanying drawings, Figure 1 is a vertical sectional view of a pump embodying my invention. In this view the parts are shown in the position of rest. Fig. 2 is a vertical section drawn on the line A B of Fig. 1. Fig. 3 is a horizontal section drawn on the line C D of Fig. 1. Fig. 4 shows the apparatus at the end of the first phase of the upward stroke of the piston—that is to say, when the liquid-admission orifice is entirely uncovered. Fig. 5 is a horizontal section drawn on the line E F of Fig. 4. Fig. 6 shows the piston at the end of its upward stroke. Fig. 7 represents the apparatus at the end of the first phase of the downward stroke of the piston—that is to say, when the liquid-admission orifice is closed. Fig. 8 shows the apparatus regulated so as to produce no useful effect.

In the various figures like letters indicate like parts.

The structure consists in principle in employing a differential piston the lower part of which is of smaller diameter and has only for effect to deliver the oil, while the upper part is of larger diameter and is intended to establish contact of the movable cylinder with the edge of the delivery-orifice, at the same time assuring a perfect joint. Moreover, with this view channels are formed in the movable cylinder, so as to allow the liquid to arrive as far as under the lower face of the larger piston in such manner that the liquid which is thus imprisoned at the moment of delivery assures a perfect joint not only between the movable cylinder and the delivery-passage, but also between this movable cylinder and the piston of small diameter.

My improved pump comprises a differential piston the lower part a' of which is of

smaller diameter and has for its object to give the liquid into the delivery-opening d , while the upper part a^2 is of larger diameter and is solely intended to draw up a certain quantity of liquid and then to press on this liquid so as to strongly press the movable cylinder onto its seat c and to assure a perfect joint, as will be described hereinafter. The double piston $a^1 a^2$ receives its constant to-and-fro movement from any suitable mechanical arrangement and is located in a movable cylinder which has two parts $b^1 b^2$ of different diameters, corresponding, respectively, to those of the pistons $a^1 a^2$. In the lower part b^1 of the movable cylinder are made channels p , opening at one end into the space in the part b^2 below the piston a^2 and at the other end into a circular space q , arranged so as to communicate with the interior of the receiver g when the movable cylinder arrives at the top of its stroke. The movable cylinder moves at its lower part in a guide r , having teeth or projections s , which allow the liquid contained in the receiver g to enter the circular space q when this cylinder is at the top of its stroke. In this guide r are formed, in addition, openings t , which during the period of admission enables the liquid contained in the receiver g to enter the cylindrical space c' in the seat c . This space c' is closed at its lower part by the escape-valve e . The useful stroke of the piston is regulated by varying the position of the sleeve f , which is secured in its regulated position by the lock-nut h .

The different parts of the pump being in the position shown at Fig. 1, the apparatus works as follows: The double piston $a^1 a^2$ in moving upward carries with it by friction during a part of its stroke the movable cylinder until this latter comes against the abutment-sleeve f , Fig. 4. The movable cylinder is therefore no longer on its seat c and the circular space q comes opposite the teeth or projections s in such manner that there is communication between the interior of the receiver g and the channels p . The double piston continuing to rise, the piston a^2 produces a suction of the liquid through the channels p and into the interior of the free space which is at the lower end of this piston. When the double piston is at the top of its stroke, Fig. 6, the lower piston a^1 is entirely out of the cylindrical space c' , and the liquid of the receiver g enters freely through the openings t into the space c' . The piston then descends and takes with it the movable cylinder, which is applied to its seat c , Fig. 7. The circular space q is then stopped by the sides of the guide r . In the continued downward motion of the piston the piston a^1 delivers, on the one hand, the liquid to be distributed contained in the space c' by forcing this latter to push back the retaining-valve e . On the other hand, the liquid below the piston a^2 is also driven. This liquid cannot flow except through the play left between the mov-

able cylinder and its guide r , and the delivery will be made with a greater resistance in proportion to the smallness of play left between this movable cylinder and its guide. There results, therefore, from this resistance to the delivery a pressure on the upper surface of the part b^1 of the movable cylinder, which has the effect of applying this latter firmly to its seat c . Again, the liquid thus compressed has the effect of opposing any escape between the piston a^1 and the part b^1 of the movable cylinder. Under these conditions it is insured that the volume of liquid which has entered the space c' during the period of admission will be completely delivered.

In order that the volume of liquid distributed at every stroke of the piston may be ascertained, I have devised the following arrangement: The upper piston a^2 passes through the regulating-sleeve f and is provided with a cylindrical space u , the interior diameter of which is equal to that of the lower piston a^1 , and in this space is located a rod v , which is fixed rigidly to the movable cylinder by means of the cross-pin w . In order to permit of relative movement between the piston and its guide or cylinder, a slot x is made in the piston. The end of the rod v is flush with the end of the piston a^2 when the latter is at the bottom of its stroke, Fig. 1. During the first phase of the upward stroke of the piston as the movable cylinder is moved by the latter the end of the rod v remains always at the same level as the end of the piston a^2 , Fig. 4. On the contrary, during the second phase of the upward stroke of the piston as the movable cylinder is stopped by the abutment-sleeve f the rod v remains immovable and the piston a^2 continues to rise. When this piston has arrived at the top of its stroke, Fig. 6, the volume of the space y will correspond exactly with the volume of liquid which should be delivered by the piston a^1 in the course of its descent. When the abutment-sleeve f is placed in a position enabling the movable cylinder to accompany the piston through its entire stroke, Fig. 8, it will be noted that the volume of liquid delivered is nothing, and in this case the end of the rod v remains always at the level of the end of the piston a^2 .

I claim—

1. In a pump, the combination of a differential piston, a movable cylinder co-operating therewith, a fixed valve-seat with which the cylinder co-operates, said piston being of different diameters and the part thereof having the smaller diameter being adapted to drive the liquid which has entered the space in the fixed seat into the delivery-passage, whereas the part of the piston which has the larger diameter is adapted to suck up a certain quantity of liquid and then to press upon this liquid so as to forcibly apply this movable cylinder to its seat and thus insure a perfect tightness, substantially as herein set forth.

2. In a pump, the combination of a piston

having a cylindrical space the interior diameter of which is equal to that of the lower end of said piston and in which space is located a rod and a movable cylinder coöperating with said piston and to which cylinder the rod is fixed, the end of the rod being flush with the end of the upper portion of the piston when the latter is at the bottom of its stroke, so that when this piston is at the top of its stroke the difference of stroke between the piston and its inclosed rod produces in the interior of this piston a space the volume of which corresponds to that of the liquid which will be driven out by the lower piston during its descent, substantially as herein set forth.

3. The combination of a casing having suction-and delivery ports, a cylinder movable relatively to the casing and having a chamber

adapted to communicate with the suction-port of the casing, said cylinder being adapted in one position to interrupt the direct communication of the interior of the casing with the outlet-port thereof, a piston arranged to move in said cylinder and in frictional engagement therewith so that it may carry the cylinder along with it, and an adjustable stop located in the path of the cylinder to regulate the quantity of fluid delivered by the pump.

The foregoing specification of my improvements in pumps for liquids or gaseous bodies and for various uses signed by me this 17th day of April, 1899.

JEAN NÉPOMUCÈNE HOCHGESAND.
